CIGARETTE STUB EXTINGUISHER

Elmer E. Moberg, Chicago, Ill.

Application January 3, 1940, Serial No. 312,272

1 Claim. (Cl. 131—237)

This invention relates to cigarette stub extinguishers and has for an object to provide a cigarette stub extinguisher which can be applied to the edge of an ash tray.

A further object is to provide a cigarette stub extinguisher adapted to cut the lighted end off a cigarette.

A further object is to provide an ash tray into which the lighted end of the cigarette drops when severed, thus preventing the fingers from becoming blackened or stained, as is the case when a cigarette is pressed against the sides of an ash tray by the fingers.

A further object is to provide a device of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification:

Figure 1 is a perspective view of the device applied to the edge of an ash tray, shown by dotted lines.

Figure 2 is a top plan view of the device.

Figure 3 is a bottom plan view of the device.

Figure 4 is a sectional view taken on the line 4—4 of Figure 2, looking in the direction of the arrows, an ash tray and cigarette being shown in dotted lines.

Figure 5 is a cross sectional view taken on the line 5—5 of Figure 4, looking in the direction of the arrows, and showing a cigarette in dotted lines.

Figure 6 is a cross sectional view taken on the line 6—6 of Figure 4, and showing a combined gauge wire and stop member.

Referring now to the drawing in which like characters of reference designate similar parts in the various views, 10 designates a plate of angular formation in cross section having a top member 11 adapted to overlie a tray 12, and a vertical member 13 extending downwardly from the top member 11 upon the inside of the tray well. A plate 9 is secured to the vertical member 13 by rivets 5 and extends downwardly upon the out-

side of the tray wall. The plate has an offset 8 adapted to abut the top edge of the tray and coact with a set screw 7 carried by the plate to secure the extinguisher to the wall of the tray. The top member 11 is provided with a central opening 14 into which a cigarette stub 15 may be inserted with the burning end downward. A combined gauge wire 16 and stop member 6, formed from a single length of wire, is disposed below the opening 14 in the top member 11, and is secured at one end to the vertical member 13 by one of the rivets 5. The gauge wire 16 limits the extent of insertion of a cigarette stub through the opening 14.

Blades 17 disposed immediately below the top member 11, provide means by which the burning end of the cigarette stub 15 may be cut off. The blades 17 are pivotally connected at their rear ends, and are secured to the top member 11 by a single pin 18. The blades are normally held in opened relation by a spring 19, the front ends of which straddle the pivoted ends of the blades, and are terminally engaged against ears 22 on the ends of the blades. The blades extend through a slot 20 in the vertical member 13 and outside of the slot are formed to provide finger pieces 21 through the medium of which they may be conveniently closed.

The stop member 6 extends centrally across the slot 20 until it abuts against the underside of the top member 11. The finger pieces 21 may be pressed inwardly to move the blades 17 in the direction of each other through the slot 20 until notches 23 formed in the blades engage around the stop member 6 when the blades reach their fully closed relation.

The extinguisher can easily be secured to the side of an ash tray simply by placing the extinguisher over the upper edge, then by tightening the securing screw 7 it is secured held in place.

When it is desired to extinguish a cigarette stub the lighted end is inserted into the opening 14 until it rests against the wire gauge 16. The finger pieces are then forced together to cause the blades 17 to slide over one another on the pivot 18 until the notches 23 engage around the upper portion of the stop member 6. The lighted end of the stub has been cut off at this point. When the finger pieces 21 are released the spring 19 returns the blades to open or normal position.

From the above description it is thought that the invention will be fully understood without further explanation.

What is claimed is:

In a cigarette extinguisher having a support

of angular cross section, one member of the support being provided with an opening through which a cigarette may be inserted with the burning end downward, said member having spring pressed blades pivoted at one end thereon and movable across said opening to sever the burning end of the cigarette, and said blades projecting through a slot in the other member of the support and terminating in finger grips for closing

the blades; a combined gage and stop comprising a single length of wire bent in right angular form, one leg of the wire being secured to the slotted member of the support and projecting across the slot thereof to limit closing movement of the blades, and the other leg projecting across said opening to limit the extent of insertion of the cigarette end through said opening.

ELMER E. MOBERG.
